UNITED STATES PATENT OFFICE.

ELISHA E. STRONG, OF PARIS, FRANCE, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed February 21, 1924. Serial No. 694,211.

To all whom it may concern:

Be it known that I, ELISHA E. STRONG, a citizen of the United States, residing in the city of Paris, Republic of France, have invented certain new and useful Improvements in Combined Typewriting and Computing Machines, of which the following is a specification.

This invention relates to computing machines, and is herein illustrated as applied to an Underwood bookkeeping machine.

In an Underwood bookkeeping machine, the different digits of a number may be indexed either for addition or subtraction, and, after the indexing has been completed, computation of the number indexed may be effected by means of a general operator, and the result shown in a register comprising dials or number-wheels, the carry-over between successive denominations being effected during the return movement of the general operator. To guard against accidental displacement of the dials, provision may be made of means to lock the dials when the general operator is either in advanced position or in its normal position. Usually at the end of a computation, the machine is so set that, upon typing a result and actuating the general operator, the register will be cleared. As a check on the carrying operation, provision may be made of a star-key locked against operation when any dial-wheel is displaced from "0" position, and of means actuatable by the star-key to print a star on the work-sheet to indicate that the register is clear.

In certain classes of work, as, for example, in banks, in counting consecutively numbered coupons or dividend warrants, it is desirable to write or type the low serial number in one column, the high serial number in another column, and the number of coupons or the like in a third column. It will be seen that the number of coupons is not the difference between the highest serial number and the lowest serial number, but is greater than such difference by one unit.

An object of the present invention consists in the provision of mechanism for computing the number of articles in a series of consecutively numbered articles when the computing mechanism is operated in succession

in accordance with the serial numbers of the articles at the opposite extremes of the series.

A feature of the invention consists in the provision of means for actuating the dial of units denomination one step to show "1" on the dial before typing and computing the numbers on the coupons at the extreme ends of the series. In the embodiment of the invention herein disclosed, such preliminary actuation of the units dial is effected by the star-key in its usual operation to print a star on the work-sheet to indicate that the register is clear.

Another feature of the invention consists in the provision of such locking means for the units dial as to prevent overthrow of the units dial and to lock it against accidental displacement when the general operator is in its normal position and at the same time to permit actuation of the units dial by the star-key.

Another feature of the invention consists in the provision of means to prevent more than one advance movement of the units dial preparatory to such typing and computation of the highest and lowest coupon numbers. According to the present embodiment of the invention, this desideratum is met by the means operated by the dial-wheels for locking the star-key, upon its return in a previous actuation, against operation when any dial is shifted from its "0" position. Obviously, the star-key may be actuated when the register is clear, and, according to the present invention, will turn the dial through one step. The star-key lock will then become effective to prevent further advance of the units dial by the star-key.

A further feature of the invention consists of means, including a register to be used in combination with the coupon-counting register, to accumulate the results computed in the coupon-counting register, and thereby register the total number of coupons in all of the packs. Preferably this result is obtained by means of a reverse-dial register, such as heretofore in use in Underwood bookkeeping machines, into which the number of coupons in a pack is added concomitantly with the subtraction of the number from the coupon-counting register to clear the latter.

Other features and advantages will hereinafter appear.

In the accompanying drawings,

Figure 1 is a sectional side elevation, 5 showing a portion of an Underwood book-keeping machine with the invention applied thereto.

Figure 2 is a perspective view, showing the lock or detent for the units dial-wheel, 10 so constructed as to permit actuation of the units dial-wheel by the clearance-proving key.

Figure 3 is a perspective view similar to Figure 2, but showing the opposite side of 15 the lock for the units dial-wheel.

Figure 4 is a diagrammatic view, indicating the manner of typing on a work-sheet the low and high serial numbers in packs of coupons and the total number of coupons in 20 the different packs and the method of computing in one register the number of coupons in each pack and in another register the total number of coupons in all of the packs.

Upon the depression of numeral-keys 11, 25 the corresponding key-levers 12 are actuated in the usual manner to effect typing, and links or pendants 13, pivoted at their upper ends to the numeral-key-levers 12, strike arms 14 projecting laterally from shafts 15, 30 of which there is one for each significant digit. Each pendant 13 acts on the corresponding arm 14 to rock the corresponding shaft 15, and, by means of an arm 16 fixed on the shaft, transmits motion to an upper 35 bar 17 of an indexing linkage and causes a corresponding setting bar 18 to depress or set a pin or member 19 on one of a series of denominational members or bars 20. Normally, such bars 20 are held in such 40 normal or rearward positions that the pins 19 lie opposite the intervals between the setting bars 18. When, however, the typewriter carriage (not shown) passes through a computing zone, the denominational members or computing bars 20 are advanced, 45 one by one, from left to right, as illustrated in the patent to A. G. Kupetz, No. 1,452, 162, dated April 17, 1923, to bring the pins 19 thereon under the setting bars 18, so that 50 depression of a numeral-key 11 will effect the depression or setting of the corresponding pin 19.

After all of the digits in the number have 55 been typed and indexed on the pins 19 of the denominational members 20, the general operator may be actuated manually by means of a handle (not shown) on a shaft 21, or by means of a motor-operating device (one form of which is shown in the patent to A. J. Wood, No. 1,299,646, dated April 8, 1919) acting through an arm 22 projecting upwardly into a fork or yoke 23 fixed on a rack-bar 24 forming part of the general operator 25. It will be seen that the shaft 21 is operatively connected with the rack-

bars 24 of the general operator by means of toothed sectors 26 fixed on shaft 21 and meshing with pinions 27, which, in turn, mesh with said rack-bars 24.

In the forward movement of the general 70 operator, a cross-bar 28 thereon is brought into engagement with the lower ends of the depressed or set pins 19 and thereby advances the denominational members 20 distances corresponding to the digits indexed, 75 such forward motion of the denominational members 20 being transmitted by racks 29 meshing with pinions (not shown), to turn dials or number-wheels 30 mounted on a member or rod 30^a forming part of a register 31 to cause results to be displayed at a sight-opening 32 in the computer casing 33. It should be understood that the pinions which are actuated by the racks 29 have 80 one-way connections with the corresponding dials, carry-overs between dials of successive denominations being effected by a suitable carry-over mechanism comprising a shaft 34 having such a one-way connection with the 85 general operator 25 as to be actuated during 90 the return movement thereof.

To set the machine for subtraction, provision may be made of a subtraction-key 35 on the forward end of a link 36 pivoted at its rear to an upright arm 37 fixed on a 95 transverse shaft 38 carrying a hook 39 normally held in engagement with a shoulder 40 on a subtraction-bar 41 by means of a spring 42 to hold the subtraction-bar 41 in forward position against the action of a 100 spring 43. Upon depression of the subtraction-key 35, the subtraction-bar 41 is released to move rearwardly under the action of the spring 43, and, in such rearward movement, a pin 44 on the subtraction-bar, 105 projecting into a slot 45 in an arm 46, acts to rock a shaft 47 upon which said arm 46 is mounted. Through connections including a second arm 48, fixed on the shaft 47 and having a pin-and-slot connection 49 with an arm 50 fixed to a transverse bar 51, 110 pivoted near its upper edge and extending into notches 52 in the shafts 15, the rocking of the shaft 47 acts to advance the shafts 15 and thereby change the connection between 115 the same and the bars 17 of the indexing linkages, so that the pins 19 complementary, to the base nine, to the values of the digits on the keys will be set by the keys 11.

Concomitantly with the forward shifting 120 of the shafts 15, all of the "9" pins on the denominational members 20 are set, and, when the machine has thus been set for subtraction, depression of any one of the numeral-keys 11 will effect the setting of the pin 19, of complementary value, on the denominational member 20 selectively advanced by the carriage, and at the same time a bar 53 will be depressed to engage 125 the rear end of a lever 53^a and restore to 130

normal position the "9" pin on the selected member 20. The subtraction-setting mechanism may be such as heretofore used in the Underwood bookkeeping machine, one form 5 of such mechanism being shown in the hereinbefore-mentioned patent to A. G. Kupetz, No. 1,452,162, dated April 17, 1923.

Fixed to each of the dial-wheels is a gear-wheel 54 which may form part of the carry-over mechanism, and which may also be utilized for other purposes. To prevent overthrow at the end of a forward movement of the general operator 25, and at the 10 end of a carry-over action effected by the return of the general operator to its normal 15 position, provision may be made of a plurality of levers or stops 55, which may be pivoted on a fixed rod 56, so that a tooth on the forwardly-extending arm of each 20 lever 55 may project into a notch between successive teeth of the corresponding gear-wheel 54. The levers or stops have rearwardly-extending arms 57 provided with teeth 58 which may be operated by suitable 25 means to prevent overthrow at the end of a carry-over operation, one form of means for operating said lever 55 in this manner being illustrated in the patent to J. N. Thornton, No. 1,228,148, dated May 29, 1917.

30 The pivoted levers 55 are also provided with projections extending downwardly and rearwardly from the arms 57 to form hooks 59 to be engaged by a bail 60 comprising a transverse bar 61 supported at its 35 ends in arms 62 mounted on a transverse shaft 63 the movement of which is controlled by means of a rearwardly-extending arm 64 having a downturned rear end to be engaged by cams 65 and 66 mounted 40 in any suitable manner on one of the general-operator rack-bars 24, so as to engage the rear end of the arm 64 when the general operator 25 approaches either its 45 extreme forward position or its extreme rearward position, respectively, thus holding the transverse bar 61 against upward movement and locking the pivoted levers 55 in effective position to prevent rotation of the dials 30.

50 Upon completion of a computation, it is customary to change the state of the computing mechanism, and, concomitantly with the typing of the result on a work-sheet, to clear the register. In order to test and indicate the correct copying of the result, provision may be made of means, operable only when the register is clear, for printing a clearance-sign, usually a star, adjacent the result. In the form of the proving device 55 herein disclosed, a clearance-proving or star key 67, mounted on a plunger 68 and normally held in raised position by means of a spring 69, is provided with a rearwardly-extending projection 70 to co-operate with a bail 71 swingable about a fixed axis 72

and urged out of the path of the projection 70 by means of a spring 73 connected at one end to the bail 71 and at the other end to a fixed plate 74 at one end of the register 31.

The position of the bail 71 may be determined by pivoted detents 75, one for each gear-wheel 54, and having projections 76 to engage between the teeth of the gear-wheels 54, the size of the projections 76 being such that each detent 75 will be held far enough away from the common axis of the gear-wheels to position the bail 71 beneath the rearward projection 70 on the star or clearance key 67, thereby locking such key against depression. When, however, each 80 of the dials 30 is so positioned as to display "0" at the sight-opening, the projections 76 on the detents 75 will be permitted to move closer to the axis of the dials 30, due to the cutouts 77 on the operatively positioned 85 teeth, and the bail 71 will be ineffective to lock the key 67. As soon, however, as any one of the dials 30 is moved from "0" position, the corresponding detent 75 will be pressed forward to a sufficient extent to 90 render the bail effective for locking the star-key. One form of such star-key-locking mechanism is disclosed in the patent to B. C. Stickney, No. 1,396,348, dated November 8, 1921.

95 When the dials 30 are in their "0" positions, the star-key 67 may be depressed to swing downwardly an arm 78 mounted on a shaft 79 and engaging a lug 80 projecting laterally from an arm 81 fixed on the shaft 100 79, the connection between the arm 78 and the shaft 79 being such that downward swinging of the arm 78 will rock the shaft 79, but rocking of the shaft 79 may be effected independently of the arm 78, as, for example, by a star-key for another register. Fixed on the shaft 79 is an upwardly-projecting arm 81 having a tooth 82 normally underlying a pin 83 on a link or pendant 84 connected, near its upper end, by a pivot 105 85 to an arm 86 fixed on a shaft 87, the lower end of the link being urged forwardly by means of a spring 88 connected at one end to the upper end of the link 84, and at its other end to an upwardly-projecting 110 lug 89 on the arm 86. The forward movement of the lower end of the link 84 may be limited by the shaft 79.

115 The arm 86 is urged downwardly by a spring 90, so that, when the tooth 82 on the upwardly-projecting arm 81 is shifted forwardly out of the path of the pin 83 by depression of the star-key 67, the shaft 87 will be rocked and a suitable clearance-sign, such as a star, printed on the work-sheet. 120 The connections through which this operation is effected comprise an arm 99^a fixed on the shaft 87, a link 91 connected with arm 90^a by a pivot 92, and a lever 93 connected with the upper end of the link 91 125 130

by a pivot 94 and corresponding to the key-levers 12. The star-key mechanism may be restored to normal condition by operating the general operator 25, thereby causing 5 a cam 95 on the carry-over shaft 34 to engage a lateral projection 92^a on the arm 86 and raise the link 84 sufficiently to permit the pin 88 thereon to be supported by the tooth 82. It should be understood that the 10 Underwood bookkeeping machines now in use have star-key mechanism, one form of which is disclosed in the patent to F. A. Hart, No. 1,190,287, dated July 11, 1916.

In the form of the invention herein disclosed, use is made of the star-key 67 to advance the units dial of the coupon-counting register from a "0" reading to a "1" reading, preliminary to typing the high and low serial numbers of a bunch or pack of 15 consecutively numbered coupons and computing the difference between said serial numbers, the result registered being one unit more than said difference and indicating the number of coupons.

For effecting such preliminary advance movement of the units dial, provision may be made of an arm 96 loosely mounted on the shaft 79 and in spaced relation to the arm 78, to which it is rigidly connected by 20 means of members or pins 97, a link 98 connected with the arm by means of a pivot 99, a lever 100 pivoted to turn about the rod 30^a forming a common axis of the dials 30, and a pawl 101 on the lever 100 to engage 25 the gear-wheel 54 attached to the units dial and to advance it one step at a time. The lever 100 is positioned just outside the right-hand plate 74 of the register, and is provided with an arcuate slot 102 through which 30 extends the shank of a screw 103 threaded into the plate 74. It will be seen that the screw 103 serves to hold the lever 100 in position relatively to the plate 74 and may also be used to limit the rocking movement of 35 the lever.

As illustrated in Figure 2, the lever 100 is provided with an offset 104 on which the pawl 101 is pivoted, preferably by means of a screw 105. The pawl 101 is urged to effective position by a spring 106 secured to the lever 100 by a screw 107, and the movement of the pawl 101 under the urging of the spring is limited by a stop or pin 108 projecting downwardly from the pawl to engage the outer face of the lever.

Usually the levers or stops 55 are substantially rigid and not only serve to prevent overthrow but actually lock the dials 30 against movement when the general operator 60 25 is in its normal rearward position. To enable the units dial to be advanced by the star-key 67, the lever 55, associated with the units dial, is articulated or made in two parts 109 and 110. The part 110 is mounted 65 on the part 109 by means of a pivot 111, and

its movement is limited by rearwardly-extending fingers 112 on opposite sides of a pin 113 secured in the part 109, the part 110 being urged to its normal position by a spring 114 coiled around the pivot 111 and 70 having its opposite ends engaging, respectively, a projection or pin 115 on the part 109 and the free end of the part 110. It should be understood that the spring 114, although strong enough to prevent overthrow of the units dial, at the end of the stroke of the associated computing bar will permit said units dial to be advanced one step by the star-key 67.

In order to obtain the sum of the numbers of the coupons in a plurality of bunches or packs, use is made of a reverse-dial register, which may be of the form in use in the Underwood bookkeeping machines, so that concurrently with the clearing by subtraction of the number of coupons in a pack from the register in which such numbers are computed, the number will be run into the reverse-dial register additively and the total 80 number of coupons in the different packs will be computed and registered in the reverse-dial register. Hereinafter, for convenience, reference will be made to the reverse-dial register as register No. 1 and to the other register as register No. 2.

An illustration of the work to be done is given in Figure 4. By suitably setting addition and subtracting stops on the carriage, in a well-known manner, the bookkeeping machine may be made to subtract from register No. 2 a number typed in a first column 85 of a work-sheet 116; to add into register No. 2 a number typed in a second column; and to subtract from register No. 2 a number typed in a third column, and concomitantly 90 add this number into the reverse dials of register No. 1.

Assuming register No. 2 to be clear and the typewriter-carriage in position for typing in the first column, depression of the 100 star-key 67 causes a star to be printed in the first column of the work-sheet, and one unit to be added into register No. 2. The low serial number 88 in the first pack of coupons is then typed in the first column and subtracted from register No. 2, thereby positioning the dials to correspond to the negative result (-87); the high serial number 90 is typed in the second column and added into register No. 2 to cause the dials thereof 105 to show "3," the number of coupons in the first pack; and the result "3" is then typed in the third column, subtracted from register No. 2 to clear the same, and concomitantly 110 run into register No. 1, giving a reading +3.

Inasmuch as register No. 2 has been cleared, the star-key 67 may be depressed to print a star in the third column to indicate clearance and to run one unit into register 115 No. 2 preparatory to computing the number 120 130

- of coupons in another pack having for the low and high serial numbers 94 and 127, respectively. Upon typing "91" in the first column and subtracting it from register No. 2, the dials of this register will be positioned to correspond to a negative result (-90). Upon typing "127" in the second column and adding it into register No. 2, the latter will indicate +37; and, upon typing "37" in the third column and running it into both registers, register No. 2 will be cleared and 37 will be added to "3" in register No. 1, giving "40" as the number of coupons in the two packs.
- 15 Variations may be resorted to within the scope of the invention, and portions of the improvements may be used without others. Having thus described my invention, I claim:
- 20 1. In a computing machine, the combination with a register having denominational dials, of numeral-keys, means operated by the actuation of said keys to perform a correct computation between two numbers, and means including a special key to make the result spurious to vary from the correct result by a definite amount.
- 25 2. In a computing machine, the combination with a register having denominational dials, of numeral-keys, means operated by said keys to effect a computation which is the difference between two numbers, a special key, and means operated by the actuation of said special key to effect a spurious result greater by one than the difference between such numbers.
- 30 3. In a computing machine, the combination with a register having denominational dials, of numeral-keys, a proving key de-pressible only when said register is clear, and means controlled by the actuation first of said proving key and then of said numeral-keys, in accordance with the digits of the highest and lowest serial numbers of a series of consecutively numbered articles, for actuating said dials to register a result greater by one than the difference between such numbers and consequently the number of articles in said series.
- 35 4. The combination with typing mechanism comprising a character-key to cause typing of a corresponding character, of a dial-wheel operable by said key, means to operate said dial-wheel, and means operable by said dial-wheel to prevent a succeeding actuation of said key until the dial-wheel has been restored to "0" by said first-mentioned means.
- 40 5. In a computing machine, the combination with a register including denominational dials, a proving key, and means to lock said proving key when any one of said dials is out of "0" position, means actuatable by said proving key to advance the units dial one step from "0" position to add one,
- 45 numeral-keys, and numeral-key-controlled subtraction mechanism to act on said register after the operation of said proving key, to cause the reading of the register to be one greater than the difference between two numbers computed as a result of the depression of said numeral-keys and the consequent addition operation; and therefore display the number of consecutively numbered units in a series having such numbers as the high and low numbers in the series.
- 50 6. In a computing machine having a register including denominational dials, in combination, numeral-keys, numeral-key-controlled subtraction-mechanism to compute the difference between two numbers, a special type-key, means to print a special character by said special key, and mechanism operable by said special key to advance the units dial one step prior to such subtraction to cause the register to indicate a spurious result at the end of the subtraction operation, which result is one greater than the actual difference.
- 55 7. In a computing machine having a register including denominational dials, in combination, numeral-keys, numeral-key-controlled subtraction-mechanism to compute the difference between two numbers, a special type-key, means to print a special character by said special key, mechanism operable by said special key to advance the units dial one step prior to such subtraction to cause the register to indicate a spurious result at the end of the subtraction operation, which result is one greater than the actual difference, and means to prevent a successive actuation of said special key to advance the dial until the register has been cleared.
- 60 8. In a combined typewriting and computing machine, in combination, a register having dials, numeral-keys, a proving key to print a symbol to indicate the clearing of the register, locking means controlled by the dials to prevent actuation of the proving key when any dial is out of "0" position, means operable by said numeral-keys to actuate said dials, and means operable by said proving key to operate one of said dials to register in said register a spurious result.
- 65 9. In a combined typewriting and computing machine, in combination, a register having dials, numeral-keys, a special key, means controllable by said numeral-keys to actuate said dials, means actuatable by said special key to actuate one of the dials, the effect of the numeral-keys and of the special key being to register a spurious result in the register, and means to prevent more than one operation of said special key in each of such computations.
- 70 10. In a computing machine, the combina-

tion with a register having denominational dials, of a proving key depressible only when all of said dials are set at "0", and means to prevent two successive operations 5 of said proving key.

11. In a computing machine, the combination with a register having denominational dials, of a proving key depressible only when all of said dials are set at "0", 10 and means, actuatable by said proving key, to prevent two successive operations of said proving key.

12. In a computing machine, the combination with a register having denominational dials, of a proving key depressible only when all of said dials are set at "0", 15 and means, actuatable by said proving key, to shift one of said dials from its "0" position, and thereby lock said proving key.

13. In a computing machine, the combination with a register having denominational dials, of a proving key depressible only when all of said dials are set at "0", 20 means operable by the proving key to advance the units dial one step, and means operable by said dial to lock said proving key, upon its return against a subsequent operation.

14. In a computing machine, the combination with a register having denominational dials, of numeral-keys, means operated by the actuation of said keys to perform a correct computation between two numbers, means including a special key to 35 make the result spurious to vary from the correct result by a definite amount, and means associated with the dials to prevent a successive operation of the special key before the dials are all returned to "0".

15. In a coupon-counting machine, the combination with a register comprising denominational elements, of numeral-keys, numeral-key-controlled devices for setting up numbers, means to actuate said devices 45 after they have been set to actuate the denominational elements to compute the difference between two numbers, a special key, and means actuatable by said special key to operate one of the denominational elements one step, 50 and thereby effect the registration of a spurious result.

16. In a computing machine, the combination of numeral-wheels, settable elements to actuate said wheels simultaneously, one 55 of said elements for each wheel, a special key to actuate one of said wheels independently of the associated settable element, and devices normally effective to hold the numeral-wheels locked against actuation, one 60 of said devices being articulated and resilient to yield when the associated wheel is operated by the special key.

17. In a computing machine, the combination of numeral-wheels, settable elements 65 to actuate said wheels simultaneously, one

of said elements for each wheel, a clearance-proving or special key operable only when the wheels are in their "0" position to actuate one of said wheels independently of the associated settable element, devices normally 70 effective to hold the numeral-wheels locked against actuation, and means including an element to lock the wheel-locking devices, the locking element being releasable to enable the wheels to be actuated by said settable elements, one of said devices being articulated and resilient to yield when the associated wheel is operated by the special key while the locking element is effective. 75

18. In a computing machine, the combination of numeral-wheels arranged in denominational order, settable computing bars to actuate said wheels, a general operator to actuate said bars, locking means normally effective to prevent accidental rotation of 80 said wheels, means effective on the initial part of the stroke of the general operator to release said locking means, so that said wheels may be rotated, and clearance-proving key-operated means to actuate the wheel of units position, said locking means including a resilient device co-operating with the units wheel to enable it to be rotated by the proving key while the rest of the locking means is effective. 85

19. In a combined typewriting and computing machine, in combination, a carriage, numeral-keys, numeral-key-actuable means for typing the digits of a number in successive denominations from higher to lower, means actuatable by said numeral-keys for indexing said digits in the various denominations as typed, denomination-selecting means operable by the carriage for said indexing means, a series of denominational dials actuatable in accordance with such indexing, a special key, special-key-controlled means for typing a special character, and special-key-controlled means to advance the units dial independently of the indexing means to produce a spurious result irrespective of the position of the carriage in which said special character is typed with respect to the position of the carriage in which the numbers are indexed. 90 100 105 110 115

20. In a computing machine, the combination of mechanism to compute the algebraic sum of any three numbers, so that said sum exceeds the difference of two of said numbers by the magnitude of the other number which is constant, and mechanism for adding the algebraic sums of successive computations, said first-named mechanism including a register, a clearance-proving key to run the constant into said register additively, means to run another number into said register subtractively, and means to run the other number into said register additively, the second-named mechanism including a register having reverse dials, so that each 120 125 130

time the algebraic sum of the three numbers is subtracted from the first-named register to clear the latter for a succeeding computation, said sum is added into the second-named register.

21. In a computing machine, the combination of mechanism to compute the algebraic sum of three numbers, so that said sum exceeds the difference of two of said numbers by the magnitude of the other number which is a constant, said mechanism including a clearance-proving key to run the constant into said register additively and means to run another number into said register subtractively, and means to run the other number into said register additively.

22. In a computing machine, the combination of a register including dial-wheels, computing bars to actuate said dial-wheels, and means to cause a spurious result to be registered in said register, said means including a device at one side of the register to co-operate with the dial-wheel of lowest order to actuate the latter independently of the computing bars.

23. In a computing machine, the combination of a register including dial-wheels, a shaft to support said dial-wheels, computing bars to actuate said dial-wheels, and a device at one side of the register and pivoted

on the dial-wheel-shaft to co-operate with the dial-wheel of lowest order to actuate the latter independently of the computing bars.

24. In a computing machine, the combination of a register including dial-wheels having a common axis, computing bars to actuate said dial-wheels, the dial-wheel of lowest order having a toothed wheel secured to the side thereof, and means to actuate the dial-wheel of lowest order independently of the associated computing bar, said means including a pivoted lever mounted to swing about the axis of said dial-wheels, and a spring-pressed pawl pivoted on said lever to engage the toothed wheel.

25. In a computing machine, the combination of a register including dial-wheel having a common axis, computing bars to actuate said dial-wheels, the dial-wheel of lowest order having a toothed wheel secured to the side thereof, and means to actuate the dial-wheel of lowest order independently of the associated computing bar, said means including a pivoted lever mounted to swing about the axis of said dial-wheels, a spring-pressed pawl pivoted on said lever to engage the toothed wheel, a key-operated arm, a link connecting said lever with said arm, and a stop to limit the movement of said lever.
